CLAIM

The ornamental design for a stackable storage unit or similar article, substantially as shown and described.

DESCRIPTION

FIG. 1 is a perspective view of a stackable storage unit or similar article showing my new design, the opposite side being a mirror image thereof;

FIG. 2 is a front elevational view thereof, the rear being flat and unornamented; and,

FIG. 3 is a bottom plan view thereof.

FIG. 3

FIG. 1

FIG. 2
